(57) **CLAIM**

We claim the design for a firearm receiver cover having an accessory mount, as shown and described in the following figures.

DESCRIPTION

FIG. 1 is a front view of a disclosed firearm receiver cover having an accessory mount.

FIG. 2 is a back view of the disclosed firearm receiver cover having an accessory mount of FIG. 1.

FIG. 3 is a view from the left of the disclosed firearm receiver cover having an accessory mount of FIG. 1.

FIG. 4 is a view from the right of the disclosed firearm receiver cover having an accessory mount of FIG. 1.

FIG. 5 is a view of the top of the disclosed firearm receiver cover having an accessory mount of FIG. 1.

FIG. 6 is a view of the bottom of the disclosed firearm receiver cover having an accessory mount of FIG. 1.

FIG. 7 is an oblique view from the top left of the disclosed firearm receiver cover having an accessory mount of FIG. 1.

FIG. 8 is an oblique view from the top right of the disclosed firearm receiver cover having an accessory mount of FIG. 1.

FIG. 9 is an oblique view from the bottom left of the disclosed firearm receiver cover having an accessory mount of FIG. 1; and,

FIG. 10 is an oblique top right view of an AK47 firearm with the disclosed firearm receiver cover having an accessory mount of FIG. 1 installed. The AK 47 firearm is not part of the disclosed design.

The claimed design is indicated by the relatively dark portions in the FIG. 10, while the relatively light portions in FIG. 10 are environmental and form no part of the claimed design. Broken lines are for the sole purpose of illustrating the environment of the article only and form no part of the claimed design.
